LEAD PENCIL SHARPENER WITH CASE

Filed Sept. 28, 1929

Inventor:

Theodor P. Möbius,

BY

James L. Potts,
ATTORNEY.

UNITED STATES PATENT OFFICE

THEODOR PAUL MÖBIUS, OF ERLANGEN, GERMANY

LEAD-PENCIL SHARPENER WITH CASE

Application filed September 28, 1929, Serial No. 395,916, and in Germany April 16, 1929.

The subject of this invention is a lead pencil sharpener, in which a case with a hinged lid is provided for accommodating the wood shavings and pencil dust produced in sharpening and in which the sharpening device is carried by the lid and adapted to be concealed or exposed according to the position thereof. Sharpening devices of this kind have the advantage that the waste materials can be stored in the closed case until opportunity arises to empty same. The pencil sharpener is therefore particularly suitable for instances when the lead pencil has to be sharpened and there is no immediate opportunity for discarding the waste, such as in a dish, waste paper basket, &c. The invention enables the sharpening device and the hinged lid of the metal case to be held by catch means, in such position that the pencil can be sharpened while the case remains closed to the escape of the shavings.

Two typical embodiments of the invention are illustrated in the drawing, in which Figure 1 represents a longitudinal section through one form, with the lid closed; Figure 2 is a longitudinal section corresponding to Figure 1 but with the lid open and the sharpener in position for use; Figure 3 is a view partly in cross section and partly in elevation taken on line 3—3 of Figure 1, and Figure 4 is a perspective view of a second embodiment with the sharpener in position for use.

Referring first to the form of Figures 1 to 3, a lead pencil sharpener 1, of taper design is attached (preferably by means of one or more screws) to a hinged lid 2, hinged at 10 to a box-shaped or rectangular case 3. The rear part of the lid 2 carries a fillet 4, of quadrangular cross section, whose outer surface forms part of the outer surface of the case when the lid is closed. Attached to the lid 2, at one side of the sharpener 1, is a catch bar 6, having a projection 7 which engages in a socket or recess 8 in the wall of the case when the lid is open or turned into the position shewn in Figure 2. In this position the lead pencil can be inserted into the conical bore 9 and turned so that it will be sharpened. The cuttings and pencil dust drop

through the knife slot into the case. If there is no immediate opportunity of discharging the contained waste, the lid 2 is closed, and the case slipped into the pocket, to be emptied when occasion offers, at which time the hinged lid can be opened fully, as indicated by the broken lines, in Figure 2.

The lid can be secured in the closed position by means of a spring, or by a second socket or recess 8a, into which the projection 7 of the bar 6 snaps.

In the embodiment according to Figure 4, the sharpening device 1 is mounted also by means of screws 2a, on the lid 2 which is adapted to turn on a hinge 10 and is provided in front with a small manipulating bulge 11. On both the broader sides of the lid, plates 12 and 13 in the form of sectors, extend downwards and are connected together in front by a curved wall 14 provided with an opening 15 for the insertion of the lead pencil to be sharpened. One side wall of the case 3 carries a very short, inwardly projecting stud 16. The sector plate 12 of the lid is provided with an arcuate groove 17, having two notches or sockets 18 and 19 into which the stud 16 is adapted to snap, depending upon the sharpening device 1, together with its lid 2, being in the position for use or in the closed position. As compared with the form of Figures 1-3, this embodiment has the advantage that the sector plates 12, 13 project further into the case when the sharpener 1 is in position for use, so that the case is effectually closed in a dust-proof manner, especially since the said plates 12, 13 slide with a spring action in the case. The case is emptied in the same manner as in the first embodiment, by turning the lid back until said plates are spaced from the case.

What I do claim as my invention and desire to obtain by Letters Patent is:—

1. In a device of the class described, a case having a container section and a closure movable relatively thereto, a pencil sharpener carried by the closure at the inner side thereof arranged to discharge shavings into the container, said sharpener being concealed in the closed position of the closure and exposed

for operation in the open position of the closure.

2. A device according to claim 1 wherein the sharpener in the open position of the lid substantially closes the container section against the escape of shavings.

3. In a device of the class described, a case having a container section, a closure section pivoted thereto along one side thereof, a pencil sharpener carried by the closure on the interior thereof, depending plates at opposite sides of the closure and at a right angle to the axis thereof, a wall connecting said plates having an opening to permit access to the sharpener, said wall and plates being located within the container section in the closed position of the closure and partly extended in the open position of the closure to permit access to the sharpener.

4. A device according to claim 3 having separable fastening means between the closure and container section to secure the closure in both open and closed positions.

5. A device according to claim 3 having separate fastening means between the closure and container section to secure the parts in both open and closed positions, said fastening means permitting the closure to swing to a position exposing the adjacent end of the container so that shavings may be emptied.

6. A device according to claim 3 wherein one of the parts of the closure has spring engagement with the container, and separable fastening means between said part and the adjacent portion of the container.

7. A device according to claim 3 in which one of the parts of the closure has spring engagement with the container, and a pin and groove connection between such part and the container, the groove enabling travel of the pin and having sockets in spaced relation to retain the pin.

In testimony whereof I have hereunto set my hand.

THEODOR PAUL MÖBIUS.
